KNITTING MACHINE

Roy C. Amidon, Fort Plain, N. Y., assignor of one-third to Walter S. Becker, Little Falls, N. Y., and one-third to Lewis M. Fowler, St. Johnsville, N. Y.

Application March 21, 1938, Serial No. 197,253

13 Claims. (Cl. 66—85)

My invention relates to certain new and useful improvements in flat knitting machines and it particularly has for its object to provide a machine for making the pile fabric disclosed in my application filed February 11, 1938, Ser. No. 190,101.

The present invention further has for its object to provide means whereby well known knitting machines now on the market can be adapted to the manufacture of pile fabric at minimum expense.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Figure 1 is an end elevation of a knitting machine embodying my invention.

Figures 2, 3 and 4 are enlarged detail views showing a needle, a sinker comb, a sinker-nib, a beard presser and a loop-pick in three of their different cooperating positions.

Figure 5 is a detail elevation of the sinker-nib and its operating instrumentalities.

Figure 6 is a detail elevation of the needle and its operating instrumentalities.

Figure 7 is a detail elevation of the beard presser and its operating means.

Figure 8 is a detail elevation of the pick and its operating means.

Figure 9 is an enlarged detail elevation of a modified sinker-nib.

Figure 10 is a detail side elevation showing how the invention may be adapted to machines in which the comb and nib of the sinker are integral, i. e., machines in which the sinker itself moves to and fro (with the comb and nib as a unit, see Patent No. 582,589, for example).

Figure 11 is a magnified and diagrammatic view of pile fabric designed to be made by the present machine.

Figure 12 is a side elevation of the fragment shown in Figure 11.

Figure 13 is a detail elevation of a portion of a pile fabric, like that of Figure 11, in which backing is incorporated.

In the drawings, in which like numbers and letters of reference indicate like parts in all the figures, the frame of the machine is composed of suitable end and intermediate frames 1 each

having feet 2, cross bars 3, 5 and 8, and longitudinal connecting bars 4 (only one of such frames being shown in the drawings, Figure 1). The cross bars 5 have bearings 6 for a shaft 7, while the bars 8 support brackets 9 for a stationary shaft 10, and brackets 11 in which a rotatable power shaft 12 turns, being driven by any suitable power applicator (not shown) in the usual way.

Bearings 13 on the frames 1 carry a shaft 14, 10 while other bearings 15 carry a shaft 16 (see Figure 1). On uprights 17 are mounted bearings 18 for two other shafts 19 and 20.

The several shafts 7, 10, 14, 16, 19 and 20 are preferably rock shafts, i. e., they are free in their bearings 6, 9, 13, 15 and 18 respectively.

Secured to the shaft 20 at suitable intervals are arms 21 which carry the sinker-nib base 22 having the usual sinker-nibs 23. The nibs 23, when the machine is adapted to making my new pile fabric, have eyes 24 through which the pile threads 1 are passed from spindles (not shown). An arm 25 is also secured to the shaft 20 and is joined by an adjustably connected connecting rod 26 to an arm 27 on the shaft 14. The arm 27 is apertured to pass the shaft 12 and is rocked in proper timed relation to other movements by cam 30 on shaft 12 which engages adjustable rollers 29 on ears 28 (see Figure 5). The number of sets of arms 21, 25, 27, and rods 26 and cams 30, used in a machine, will depend on the length of the machine, according to well known knitting machine practice. As such sets are duplicates of each other, however, only one set has been shown in the drawings. (Figures 1 and 5.)

Needle bar arms 31 secured to shaft 7 carry bearded needles 32 of any approved construction and the needles are moved by (one or more) rocking arms 33 secured to shaft 7 and are actuated by a suitable cam or eccentric 36, each arm having ears 34 that have adjustable rollers 35 to engage the cam or eccentric (see Figure 1). The number of arms 31, 33 and cams or eccentrics 36 used in a machine also depends on the length of the machine.

The beard presser bar 60 is carried by arms 37 secured to shaft 19 to which rocking arms 38 are also secured. The arms 38 each have a roller 39 to engage a suitable cam 40 secured to shaft 12, a spring 41 serving to hold roller 39 to cam 40 and effect the return movement of the presser bar 60 (see Figure 7). Like the units of Figures 5 and 6, that of Figure 7 is similarly duplicated

in the machine and the same is true with regard to the unit shown in Figure 8.

As shown in detail in Figure 8, the shaft 12 carries a cam (or cams) 47 against which roller 46 is held by action of spring 48 on roller-carrying arm 45 that is secured to shaft 16. The pick-carrying head 42 is also secured to shaft 16 and carries the loop-picks 43, the same being, preferably, removably held by suitable means 44.

10. Arms 49 fixed to shaft 10 carry the sinker-carrying bar 50 on which the sinkers are mounted in the usual way. The sinkers include the bases 51, combs 52 and sleys 53, and in certain cases integral nibs. See Figure 10, by reference to 15 which it will be seen that 54 is the base, 55 the comb, 56 the sley, 57 the nibs, 58 the eye and 59 the wires or rounded portions to allow the pile threads 1 to pass over without catching.

The usual guides for the warp threads *w* and 20 the inlay threads *i* are indicated by 61 and 62, respectively (see Figures 1, 2 and 3).

The nibs 23 (or 57) may be provided with threading slits 24^b and the eyes 24^a may be elongated if desired (see Figure 9).

25. In operation the machine is adjusted to knit the warp chains *w'* and inlays *i* in any of the well known ways and the picks 43 are adjusted to pull the pile threads 1 through between the adjacent lays of thread *i* (chain cross-connecting 30 thread), the pile threads being laid beneath the cross-connecting threads between adjacent chains *w'* and pulled into loops *l'* (see Figures 11 and 12).

35. Of course the parts are not loosely knit, as would seem to be the case in Figures 11 and 12; on the contrary, the threads are drawn sufficiently taut so that the piles *l'* will be held securely in one direction by the contact of the adjacent chain *w'* and in a direction transversely 40 thereto by the inlay or cross-connecting threads *i*.

If desired, the fabric as it leaves the sleys, or after it is taken from the machine, may have a coat of suitable adhesive *c* applied to its back or under face and also a reinforcing sheet *b* of 45 suitable material, as indicated in Figure 13.

45. The cement *c* used may, for example, be latex or a nitrocellulose cement and the backing sheet *b* may be woven or other fabric, rubber, or any other suitable material, depending on the use 50 to which the fabric is to be put.

55. While I have shown a machine of the type in which the nib 23, needles 32, beard presser 60 are given an oscillating motion, the machine may be one of the type in which these parts are given rectilinear movement as the invention is readily adaptable to either type.

60. From the foregoing description, taken in connection with the accompanying drawings, it is thought that the operation and advantages of the invention will be clear to those skilled in the art.

What I claim is:

1. In a knitting machine, means to knit parallel chains of warp threads, means to connect said chains by cross threads, means to lay pile threads beneath the cross threads, and means to pull said pile threads through between adjacent cross threads to form pile-loops between said adjacent cross threads.

2. In a knitting machine, means to knit parallel chains of warp threads, means to connect said chains by cross threads, means to lay pile threads beneath the cross threads, and means to pull said pile threads through between adjacent cross threads to form pile-loops between said adjacent cross threads, the warp and cross threads

being knit under sufficient tension to hold said pile-looped threads in place.

3. In a knitting machine, means to knit parallel rows of chains, means to inlay cross-connecting thread from chain to chain, means to lay pile threads parallel to and between adjacent chains and beneath said cross-connecting threads, and means to loop said pile threads through between adjacent cross-connecting threads.

4. The combination with a knitting machine 1 employing sinkers, bearded needles, a beard presser and means to operate the aforesaid elements to produce a knit fabric including parallel chains and cross-connecting threads between the chains, of means to lay pile threads beneath said cross-connecting threads between adjacent chains, and means to loop said pile threads through between adjacent cross-connecting threads.

5. The combination with a knitting machine 2 employing sinkers, bearded needles, a beard presser and means to operate the aforesaid elements to produce a knit fabric including parallel chains and cross-connecting threads between the chains, of means to lay pile threads 2 beneath said cross-connecting threads parallel to and between adjacent chains, and means to loop said pile threads through between adjacent cross-connecting threads.

6. In a knitting machine, means to knit parallel chains of warp threads, means to connect said chains by cross threads, means to lay pile threads beneath the cross threads, means to pull said pile threads through between adjacent cross threads to form pile-loops, said means to pull including sinkers whose nibs have eyes to receive the pile threads, and picks to engage the pile threads when the nibs and picks are adjacent and to hold the threads while the nibs and picks are being separated during the usual knitting function of the 4 machine.

7. The combination with a knitting machine employing sinkers, bearded needles, a beard presser and means to operate the aforesaid elements to produce a knit fabric including parallel chains and cross-connecting threads between the chains, of means to lay pile threads beneath said cross-connecting threads between adjacent chains, and means to loop said pile threads through between adjacent cross-connecting threads, said means to lay pile threads comprising an eye in each of the nibs of the sinkers through which the pile threads are passed and said means to loop said pile threads through and between adjacent cross-connecting threads comprising picks cooperating with the sinker nibs to engage the pile threads on the forward stroke of the sinker nibs and hold the pile threads while the sinker nibs recede and the chain threads are knocked over and the cross-connecting thread laid over the pile threads.

8. In a flat knitting machine, a set of bearded needles, a set of sinkers which include combs and sinker nibs, the nibs having eyes, a beard presser, thread guides, means to move the needles back and forth through the sinkers, means to move said nibs back and forth across the path of said needles, means to operate the beard pressers during the return strokes of the needles through the sinkers, all of said means being timed with relation one to another to produce a knit fabric of cross-connected chains, said sinker nib eyes being constructed to receive pile threads, and a pick to engage said pile threads while said nibs are in their advanced position and hold said pile threads.

while the nibs and needles are on their return strokes, in virtue of which the pile threads will be laid beneath the cross-connecting threads and be pulled between the same in pile-loops.

9. In a flat knitting machine, a set of bearded needles, a set of sinkers which include stationary combs and movable sinker nibs, the nibs having eyes, a beard presser, thread guides, means to move the needles back and forth through the sinkers, means to move said nibs back and forth across the path of said needles, means to operate the beard pressers during the return strokes of the needles through the sinkers, all of said means being timed with relation one to another to produce a knit fabric of cross-connected chains, said sinker nib eyes being constructed to receive pile threads, and a pick to engage said pile threads while said nibs are in their advanced position and hold said pile threads while the nibs and needles are on their return strokes, in virtue of which the pile threads will be laid beneath the cross-connecting threads and be pulled between the same in pile-loops.

10. In a flat knitting machine, a set of bearded needles, a set of sinkers which include combs and sinker nibs, the nibs having eyes, a beard presser, thread guides, means to move the needles back and forth through the sinkers, means to move said nibs back and forth across the path of said needles, means to operate the beard pressers during the return strokes of the needles through the sinkers, all of said means being timed with relation one to another to produce a knit fabric of cross-connected chains, said sinker nib eyes being constructed to receive pile threads, and a pick to engage said pile threads while said nibs are in

their advanced position and hold said pile threads while the nibs and needles are on their return strokes, in virtue of which the pile threads will be laid beneath the cross-connecting threads and be pulled between the same in pile-loops, said pick comprising an oscillatable member carrying picking fingers and means to move said fingers into and out of operative position in timed relation to the knitting operations performed by the needles in cooperation with the sinkers for purposes described.

11. In a knitting machine, means to knit parallel warp chains, connected by crossing inlay thread; means to locate pile-loop threads beneath the several lays of the inlay thread between adjacent chains and loop the pile-loop threads through between adjacent lays of inlay thread.

12. In a knitting machine, means to knit rows of chains; means to connect adjacent chains by threads extending across from chain to chain; means to locate pile-loop threads beneath the several lays of the cross threads and means to form pile-loops extending through the spaces between the chains and between adjacent cross threads whereby the loops are held in position by said chains and cross threads.

13. In a knitting machine, means to knit parallel chains of warp threads, means to connect said chains by cross threads, means to lay pile threads beneath the adjacent cross threads and carry the same in the form of loops between the adjacent cross threads, and means to hold the loops against receding as said laying and carrying means recedes.

ROY C. AMIDON. 35
